(57) **CLAIM**

The ornamental design for a display panel or screen with animated graphical user interface, as shown and described.

DESCRIPTION

FIG. 1 is a front elevational view of a first image of a first embodiment of a display panel or screen with animated graphical user interface showing our new design;

FIG. 2 is a front elevational view of a second image thereof;

FIG. 3 is a front elevational view of a third image thereof;

FIG. 4 is a front elevational view of a fourth image thereof;

FIG. 5 is a front elevational view of a fifth image thereof;

FIG. 6 is a front elevational view of a sixth image thereof;

FIG. 7 is a front elevational view of a seventh image thereof;

FIG. 8 is a front elevational view of an eighth image thereof;

FIG. 9 is a front elevational view of a ninth image thereof;

FIG. 10 is a front elevational view of a tenth image thereof;

FIG. 11 is a front elevational view of an eleventh image thereof;

FIG. 12 is a front elevational view of a twelfth image thereof;

FIG. 13 is a front elevational view of a thirteenth image thereof;

FIG. 14 is a front elevational view of a fourteenth image thereof;

FIG. 15 is a front elevational view of a fifteenth image thereof;

FIG. 16 is a front elevational view of a sixteenth image thereof;

FIG. 17 is a front elevational view of a seventeenth image thereof;
FIG. 18 is a front elevational view of a eighteenth image thereof;
FIG. 19 is a front elevational view of a nineteenth image thereof;
FIG. 20 is a front elevational view of a twentieth image thereof;
FIG. 21 is a front elevational view of a twenty-first image thereof;
FIG. 22 is a front elevational view of a twenty-second image thereof;
FIG. 23 is a front elevational view of a twenty-third image thereof; and
FIG. 24 is a front elevational view of a twenty-fourth image thereof.
FIG. 25 is a front elevational view of a first image of a second embodiment of a display panel or screen with animated graphical user interface showing our new design;
FIG. 26 is a front elevational view of a second image thereof;
FIG. 27 is a front elevational view of a third image thereof;
FIG. 28 is a front elevational view of a fourth image thereof;
FIG. 29 is a front elevational view of a fifth image thereof;
FIG. 30 is a front elevational view of a sixth image thereof;
FIG. 31 is a front elevational view of a seventh image thereof;
FIG. 32 is a front elevational view of an eighth image thereof;
FIG. 33 is a front elevational view of a ninth image thereof;
FIG. 34 is a front elevational view of a tenth image thereof;
FIG. 35 is a front elevational view of an eleventh image thereof;
FIG. 36 is a front elevational view of a twelfth image thereof;
FIG. 37 is a front elevational view of a thirteenth image thereof;
FIG. 38 is a front elevational view of a fourteenth image thereof;
FIG. 39 is a front elevational view of a fifteenth image thereof;
FIG. 40 is a front elevational view of a sixteenth image thereof;
FIG. 41 is a front elevational view of a seventeenth image thereof;
FIG. 42 is a front elevational view of a eighteenth image thereof;
FIG. 43 is a front elevational view of a nineteenth image thereof;
FIG. 44 is a front elevational view of a twentieth image thereof;
FIG. 45 is a front elevational view of a twenty-first image thereof;
FIG. 46 is a front elevational view of a twenty-second image thereof;
FIG. 47 is a front elevational view of a twenty-third image thereof; and
FIG. 48 is a front elevational view of a twenty-fourth image thereof.
FIG. 49 is a front elevational view of a first image of a third embodiment of a display panel or screen with animated graphical user interface showing our new design;
FIG. 50 is a front elevational view of a second image thereof;
FIG. 51 is a front elevational view of a third image thereof;
FIG. 52 is a front elevational view of a fourth image thereof;
FIG. 53 is a front elevational view of a fifth image thereof;
FIG. 54 is a front elevational view of a sixth image thereof;
FIG. 55 is a front elevational view of a seventh image thereof;
FIG. 56 is a front elevational view of an eighth image thereof;
FIG. 57 is a front elevational view of a ninth image thereof;
FIG. 58 is a front elevational view of a tenth image thereof;

FIG. 59 is a front elevational view of an eleventh image thereof;
FIG. 60 is a front elevational view of a twelfth image thereof;
FIG. 61 is a front elevational view of a thirteenth image thereof;
FIG. 62 is a front elevational view of a fourteenth image thereof;
FIG. 63 is a front elevational view of a fifteenth image thereof;
FIG. 64 is a front elevational view of a sixteenth image thereof;
FIG. 65 is a front elevational view of a seventeenth image thereof;
FIG. 66 is a front elevational view of a eighteenth image thereof;
FIG. 67 is a front elevational view of a nineteenth image thereof;
FIG. 68 is a front elevational view of a twentieth image thereof;
FIG. 69 is a front elevational view of a twenty-first image thereof;
FIG. 70 is a front elevational view of a twenty-second image thereof;
FIG. 71 is a front elevational view of a twenty-third image thereof; and
FIG. 72 is a front elevational view of a twenty-fourth image thereof.
FIG. 73 is a front elevational view of a first image of a fourth embodiment of a display panel or screen with animated graphical user interface showing our new design;
FIG. 74 is a front elevational view of a second image thereof;
FIG. 75 is a front elevational view of a third image thereof;
FIG. 76 is a front elevational view of a fourth image thereof;
FIG. 77 is a front elevational view of a fifth image thereof;
FIG. 78 is a front elevational view of a sixth image thereof;
FIG. 79 is a front elevational view of a seventh image thereof;
FIG. 80 is a front elevational view of an eighth image thereof;
FIG. 81 is a front elevational view of a ninth image thereof;
FIG. 82 is a front elevational view of a tenth image thereof;
FIG. 83 is a front elevational view of an eleventh image thereof;
FIG. 84 is a front elevational view of a twelfth image thereof;
FIG. 85 is a front elevational view of a thirteenth image thereof;
FIG. 86 is a front elevational view of a fourteenth image thereof;
FIG. 87 is a front elevational view of a fifteenth image thereof;
FIG. 88 is a front elevational view of a sixteenth image thereof;
FIG. 89 is a front elevational view of a seventeenth image thereof;
FIG. 90 is a front elevational view of a eighteenth image thereof;
FIG. 91 is a front elevational view of a nineteenth image thereof;
FIG. 92 is a front elevational view of a twentieth image thereof;
FIG. 93 is a front elevational view of a twenty-first image thereof;
FIG. 94 is a front elevational view of a twenty-second image thereof;
FIG. 95 is a front elevational view of a twenty-third image thereof; and
FIG. 96 is a front elevational view of a twenty-fourth image thereof.
The broken line showing of a display panel or screen, text and graphic elements forms no part of the claimed design.
